UNITED STATES PATENT OFFICE.

JOHN ELDER AND BRUCE M. MACLEOD, OF LETHBRIDGE, ALBERTA, CANADA.

COMBINED WIRE STRETCHER AND SPLICER.

Application filed February 27, 1923. Serial No. 621,591.

To all whom it may concern:

Be it known that we, JOHN ELDER and BRUCE MORPETH MACLEOD, subjects of the King of Great Britain, and residents of the 5 city of Lethbridge, in the Province of Alberta and Dominion of Canada, have invented certain new and useful Improvements in Combined Wire Stretchers and Splicers, of which the following is a specification.

10 This invention relates to improvements in combined wire stretchers and splicers and the objects of the invention are to provide a light, efficient and simply constructed tool of this character, in which the several parts 15 will satisfactorily perform the various functions required of them.

With the foregoing and other objects in view, the invention consists essentially in the novel construction and arrangement of 20 parts as described in the present specification and illustrated by the accompanying drawings that form part of the same.

Referring now to the drawings, in which like characters of reference indicate corresponding parts in each figure,

Figure 1 is a plan view embodying the invention and showing loose wires in position preparatory to splicing.

Figure 2 is a similar view showing the 30 stretcher reversed.

Figure 3 is a detail of the swivel mounted clamp.

Figure 4 is a detail of the clamping member.

35 Figure 5 is a plan view of the stretcher showing wire stretched preparatory to splicing.

Figure 6 is a similar view of the next position preparatory to splicing, in dotted lines.

40 Figure 7 is a plan view showing the final position of stretcher and taut wires for splicing.

In the drawings, in which an example of 45 the invention is illustrated, A designates the device as a whole consisting of a main member 10 pointed at its lower end 11 to be stuck into the ground when desired and suitably curved at its upper end to form the 50 fixed arm 12.

14 is a swinging arm suitably curved in opposition to the arm 12 and pivotally mounted on the arm 12 at 13. This arm 14 is also adjustable by means of a series of 55 holes 15 therein, one of which is designed to register in turn with a hole 16 in the arm 12.

18 is a hole in the arm 14 apart from the series 15 and is designed to register with a hole 19 in the main member 10 to receive therethrough a securing pin 20 carried by 60 the handle 10 and adapted when in use to hold the swinging arm 14 fixedly in position.

It will be noted that the semi-circular formed swinging arm 14 is adapted to extend along and lie snugly against the arm 12, thereby ensuring strength as well as efficiency in operation.

Adjacent the outer ends of the arms 12 and 14 are the clamping members 22 and 23, 70 one of which is mounted on the rear side of the arm and the other on the front of the arm. These clamps comprise a fixed portion 24, here shown as having a concaved face and a pivotally mounted cam-shaped 75 member 25 provided with teeth 26 and a handle 27 and adapted in operation to engage with the portion 24 to grip therebetween the wire.

Pivotedly mounted at 28 intermediate of 80 the ends of the member 12, is a swivel member 29 on which in turn is mounted a clamp 30 of similar construction to the clamp 23.

31 and 32 are the wires.

33 is a spring for the clamp 22 connecting the arm of the clamp 22 with the swinging arm, whereby the clamp 22 is automatically held in closed position.

With regard to the hole in the swinging arm designed to register with the orifice 90 or hole in the main member 10 and through which the pin is placed to hold the arm in position, this is for the purpose of stretching loose wires and for holding the device 95 in position for splicing the loose ends of stretched wires. All the other holes in the swinging arm are for the purpose of holding the stretcher at any point during the stretching of wire in what is known as the reverse pull or push of the handle 10 away from the 100 operator. These holes in different places enable the operator to hold and fasten the stretcher at any point in the reverse stretch by simply dropping the bolt 17 into the hole which may be in proper place for purpose.

To splice loose wires, fasten both the wires 31 and 32 in the clamp 23, place one wire 31 in clamp 22 and the end of the wire 32 place on the opposite side of the arm 14 to 110 that of the clamp 22. Give wire 32 a half turn around the wire 31 and place spike be-

tween the wires and turn it four or five times and the splice is made, see Figures 1, 2 and 7.

- To stretch wire, place the wire 31 in the swivel clamp 30 and tap clamp home securely with hammer or clippers, leaving the loose end of wire 31 long enough to extend across to clamp 22 when stretcher is in position. Then stretch movable arm 14 out to the left as far as it will go and place wire 32 in clamp 22. The loose end of wire 32 must be long enough to reach clamp 23 when the handle of stretcher is pushed over to the right as far as it will go.
- With the spring on handle of clamp 22, it will grip the wire 32 automatically when inward movement of the stretcher is begun. The finish of this pull is illustrated in Figure 5.
- The handle is then drawn to the right and in this manner the wire is stretched. Then push the handle of stretcher to the left again until it is back in its former position, and repeat these stretches until wire is tight enough to suit. The handle of the stretcher is then drawn to such a position that the orifice therein registers with the orifice in the arm 14, thereby holding the stretcher in position for splicing the loose ends.
- The loose end of the wire 31 is then given a half turn over wire 32 beyond clamp 22 and the loose end of wire 32 is given a half turn over wire 31 to the right of clamp 30, see Figure 7, and then the spike or handle of the wire clippers is placed between the two wires and turned until the wires are securely spliced between the arms. Then open clamps and remove stretcher and the work is done.
- As many changes could be made in the above construction and many apparently widely different embodiments of our invention within the scope of the claims, constructed without departing from the spirit or scope thereof, it is intended that all mat-

ter contained in the accompanying specification and drawings shall be interpreted as illustrative and not in a limiting sense.

What we claim as our invention is:

1. A tool of the character described, comprising in combination, a handle member having a rigid arm, a swinging arm carried by the rigid arm, and means for retaining the swinging arm in position, means for adjusting said arm including a series of orifices designed to register individually with an orifice in the rigid arm, and pivotal bolt means adapted to extend through said orifices, clamping means for said arms, spring actuated means for closing clamping means, and clamping means swivel mounted on the rigid arm. 50 55 60

2. In a tool of the character described, the combination with a stem, a rigid arm formed on the stem, a second arm swingingly mounted on the rigid arm, clamping means adjacent the outer ends of said arms, and a clamping member pivotally mounted on the rigid arm intermediate of the swinging arm, and the clamping member at the 65 70 outer end thereof.

3. In a tool of the character described, the combination with a rigid arm, and a swingingly mounted arm having clamping means thereon, of a clamping member pivotally mounted on the rigid arm, intermediate of the swinging arm, and the clamping means thereon, a plurality of orifices in the swinging arm adapted to individually register with orifices in the rigid arm, and pin securing means through said orifices whereby the swingingly mounted arm is fixedly and adjustably retained in position. 75 80

In witness whereof we have hereunto set our hands in the presence of two witnesses.

JOHN ELDER.
B. M. MACLEOD.

Witnesses:

ANNE M. MACKENZIE,
WILLIAM S. BALL.
